KNIFE

Fred R. Fellows, Box 464, Big Fork, Mont. 59911

Filed Nov. 15, 1972, Ser. No. 306,697

Term of patent 14 years

Int. Cl. D8—03

U.S. Cl. D8—99

Fig. 1.

Fig. 3.

Fig. 2.

Fig. 4.

Fig. 5.

Fig. 6.

FIG. 1 is a side elevational view of the knife in a closed condition;

FIG. 2 is a top plan view thereof;

FIG. 3 is a bottom plan view thereof;

FIG. 4 is an elevational view of one end of the knife;

FIG. 5 is an elevational view of the opposite end thereof; and

FIG. 6 is a side elevational view showing the knife in an opened condition.

The side opposite that shown in FIGS. 1 and 6 is a mirror image of the side shown.

I claim:

The ornamental design for a knife, as shown and described.
